(57) **CLAIM**

The ornamental design for a transportable and compactible sleep mat and cot cover for children, as shown and described.

DESCRIPTION

FIG. 1 is a left side, top and front perspective view of the transportable and compactible sleep mat and cot cover for children showing my new design and showing the sleep mat in its compacted and closed state;

FIG. 2 is a top plan view thereof;

FIG. 3 is a front elevational view thereof;

FIG. 4 is a bottom plan view thereof;

FIG. 5 is a rear elevational view thereof;

FIG. 6 is a left side elevational view thereof; and

FIG. 7 is a right side elevational view thereof.

FIG. 8 is a left side, top and front perspective view of the sleep mat showing my new design and showing the sleep mat in its uncompacted and opened state;

FIG. 9 is a left side elevational view thereof;

FIG. 10 is a top plan view thereof;

FIG. 11 is a right side elevational view thereof;

FIG. 12 is a bottom plan view thereof;

FIG. 13 is a front elevational view thereof; and,

FIG. 14 is a rear elevational view thereof.
